UNITED STATES PATENT OFFICE

2,131,464

PREFABRICATED BUILDING

Joseph C. Estes, Woonsocket, R. I., assignor to
Austin T. Levy, Harrisville, R. I.

Application November 4, 1937, Serial No. 172,834

19 Claims. (Cl. 72—1)

My invention relates to prefabricated buildings. It has among its objects to provide an improved gable end construction for prefabricated buildings of the type described in Patent No. 2,104,869 and Patent No. 2,104,870, issued January 11, 5 1938 to Austin T. Levy.

Another object of my invention is to provide an improved frame for such a gable end wall which is less expensive both to fabricate and to 10 erect, and which has improved and simplified roof supporting members at the upper end of the gable.

A further object of my invention is to provide such an improved gable end wall in which portions of the wall, including a plurality of panels and the enclosing frame members therefor, are prefabricated and ready to be erected as multi-panel units in the wall.

A still further object is to provide improved 15 frame members together with improved frame connecting means for connecting such multi-panel prefabricated wall sections together and to the adjacent frame members comprising the wall.

Still other objects are to provide improved 20 continuous reenforcing means for the cementitious coatings applied over the inner and outer faces of the wall panels following erection, improved and simplified plate means for receiving the upper and lower panel boards, improved 25 means for supporting the inclined roof supporting members of the gable wall from the lower story corner stud members, and improved connections 30 between the gable end wall frame and partition and ceiling supporting structure. These and 35 other objects of my invention will, however, hereinafter more clearly appear.

In the accompanying drawings I have shown 40 my improved construction, for purposes of illustration, in a gable end structure suitable for a dwelling.

In these drawings—

Figure 1 is an elevation of a house constructed in accordance with my invention, certain parts being omitted and others being broken away to 45 facilitate illustration;

Fig. 2 is an enlarged vertical section taken on line 2—2 of Figure 1;

Fig. 3 is a similar enlarged vertical section on line 3—3 of Figure 1;

50 Fig. 4 is an enlarged vertical section on line 4—4 of Figure 1;

Fig. 5 is a detail perspective view taken at an outside corner of the building adjacent the upper end of a corner stud, the roof supporting member of the gable end being shown in section;

Fig. 6 is an enlarged perspective view showing one of the four intermediate junctions of the plate member and upper and lower studs;

Fig. 7 is an enlarged perspective view of a special junction at the center of the gable, taken from the inside of the wall and showing a lower story partition cap, a ceiling joist, and the method of connecting the same to the gable end;

Fig. 8 is a front elevation of a prefabricated multi-panel section of the gable end wall;

Fig. 9 is a plan view of the building at the gable end thereof, showing the arrangement of the ceiling joists relative to the gable end, the connecting and reenforcing rods for these joists and a portion of the roof;

Fig. 10 is a perspective view of the junction of Figure 7, the prefabricated gable portion and lower wall stud being in process of connection, and

Fig. 11 is a view similar to Figure 10 but showing the joint of Figure 6.

In these drawings, as in the above mentioned 20 patents, I have shown my invention embodied in a dwelling house having a gable end wall, generally indicated at A in Figure 1, and having a frame comprising a lower sill member 2, an upper plate member 3, inclined roof supporting members 4, and horizontally spaced vertical studs 5 connecting these members and defining a plurality of panel apertures adapted to receive suitably shaped wall panels 6. first story panels, these channels being secured back to back, as by welding. The channels 16 and 17 comprising the plate member, as shown, are of the same size as the channels 11 and 12 comprising the studs and, at their junctions with the studs, have their flanges, or legs, cut away to the back of the channel to receive the gable and first story studs respectively. (See Figures 10 and 11.) The gable studs and the gable panels are received at their upper ends within the downwardly facing channels of the oblique roof supporting members 4; the panels in the first story and the gable thus having their entire peripheries received within the channels of the frame members. It will also be noted that the corner stud channels 13, 14 and 15 extend above the plate member and are continuous from the sill to the roof supporting frame members 4 within which the channels 13 and 14 are received, the channel 15 being shortened at its upper end and received within a downwardly depending channel member 18 comprising the plate member for the adjacent wall of the building.

Herein, the gable portion of the wall is prefabricated, comprising two generally similar left and right-hand sections, one of which is shown in Figure 8. These prefabricated sections are exactly alike except that one, here the right-hand section, carries both channels 11 and 12 of the center stud of the gable. Thus each section includes one-half of the gable wall, and a description of the right-hand section shown in Figure 8 will suffice for both. The prefabricated section shown includes one-half of the length of the plate member 3, which comprises the base of the triangular section, the channel members 11 and 12 of the center stud member 5 and one of the oblique roof supporting frame members 4; two intermediate studs 5 being provided to divide the section into 3 panel apertures, each of which carries a gable panel 6 positioned at its edges, as previously described, in the channels of the frame members. The channels of studs 5 of the gable portion at their upper ends are suitably secured to the roof supporting member 4, preferably by welding, and at their lower ends are connected to the plate member 3 by means of octagonal connecting plates 19 disposed at the junction of the stud and plate members and preferably connected thereto by welding.

As previously noted, the channels of the studs 5 and plate member 3 are of the same size and the latter are cut away to receive the ends of the studs (Figures 6 and 11) so that a flush surface is presented at the junctions of these members over which the connecting plate 19 is disposed. Except for the connecting plate at the center stud of the gable, the top edge of each connecting plate is secured to its stud 5 and the lateral edges are secured to the flanges of the plate member 3 as shown in Figure 11, this connection being made at the factory, preferably by welding. Here, it will be noted that the plates 19 project downwardly beyond the lower channel 17 of the plate member in position to overlie the studs 5 of the first story when these prefabricated sections are placed in the building wall, and as shown in Figures 6 and 11, apertures 20 are provided in the upper ends of the studs 5 of the first story, and like apertures 21 are provided in the connecting plates 19, through which bolts may be passed to facilitate connection in the field of the prefabricated section to the studs of the lower story, although these connections are also preferably subsequently welded. In the case of

the center stud of the gable, Figures 7 and 10, the plate 19 not only projects downwardly beyond the plate member, but also projects to the left to overlie the channels 16 and 17 comprising the plate member of the left-hand prefabricated section.

It will also be noted that a special plate 22 is provided at the eaves to connect the channels 16, 17 of the plate member to the roof supporting member 4, these plates being received within legs of the channel comprising member 4, and being welded thereto and to the channels 16 and 17. Plate 22 is also provided with suitable apertures which are aligned with corresponding apertures in the corner stud of the building to receive bolts during the process of erection of the wall. The roof supporting member 4 carries the end rafter of the roof, herein comprising a four by four wooden timber 23 which extends slightly beyond member 4 at the eaves and is secured thereto at spaced points by suitable spikes 24 which are nailed from within the channel 4 prior to fabricating the section.

The prefabricated gable sections also have similar plates 19 and 22 on the inner faces of the stud and plate members, although, it will be noted that at the center junction, a half plate 25 is provided which is welded to the channels 11 and 12 and extends only over the upper channel 16 of the plate member. Likewise, the inside corner plate 22 is shortened, see Figure 5, so as to terminate above the plate member 18 of the adjacent building wall.

From the above, it will be evident that the right and left-hand sections of the gable can be placed as units on the studs and panels of the first story, thus greatly facilitating the erection of the building in the field. After the two prefabricated gable sections have been placed in position in the wall, with the panels and studs of the first story received within the channel member 17, the plates 19 are welded to the upper ends of the channels 11, 12 of the intermediate first story studs, and the plate 22 to the channels 13, 14 of the corner studs to secure the sections to the remainder of the frame. Likewise, adjoining ports of each gable wall section stud at the center of the gable are suitably welded to each other, thus providing a strong and rigid connection between the frame sections.

Following the erection of the frame with the panels therein, reenforcing rods 9 are applied to the inner and outer faces of the wall, their opposite ends being received and positioned within the channels of the roof supporting members 4 and lower sill member 2; these rods, save where special closure panels occur, being continuous over the face of the building wall. The rods are secured to the panel faces in a usual manner by wire ties 9a extending through the panels and connecting corresponding rods on opposite faces thereof. As shown herein, the rods 9 are sprung around and overlie the channels 16 and 17 of the plate member and, if desired, they may be welded thereto. These rods 9 serve not only to reenforce the panels against lateral buckling stresses, but also space from the faces of the panel, the coating anchoring material 7, thus providing a space between the material and the panel faces for clinching the cementitious coating 8. Also, it will be noted that the rods 9, particularly in the vicinity of the plate member, reinforce this cementitious coating against cracking at the junction between the gable and the first story of the wall.

Ceiling supporting joists comprising channels 75

26 are provided at spaced points along the plate members 18 parallel with the gable end wall of the building, one of which (see Figures 3 and 7) is secured to the studs of the gable just above 5 the plate 3 thereof; suitable spacers 27 being provided between the back of the channel 26 and the studs 5, and other spacers 28 being provided between the back of channel 26 and the inside of 10 connecting plates on these studs, to provide space between the joist and the plate member 3 to permit the reenforcing rods 9 to pass along the inside of the wall.

The ceiling joists 26 are preferably connected by transverse connecting or bridging rods 32, 15 which are welded to the tops of the upper flanges thereof and extend at spaced points along these joists parallel to the plate members 18.

In Figure 7, I have shown a downwardly directed channel member 29 constituting the cap for 20 an inside partition located at the center stud of the gable end wall, an angle clip 30 being provided having a back portion corresponding to the half plate 25, and welded to the channels 11 and 12 of the center stud and to the inside leg of 25 channel 17 of the plate member. The angularly related leg 31 of this angle clip is also welded to the back of channel 29.

As a result of my improved construction, the 30 erection of the gable end wall of buildings of this type is greatly facilitated. It will be evident that, following the erection of the first story studs and panels, these prefabricated gable sections can be quickly and easily placed in position and welded to the first story framework, thus completing 35 the erection of the frame and the roof supporting structure. Also, it will be evident that the provision of reenforcing and spacing rods which extend continuously over the panels from the roof to the sill, provides a stronger end wall and one 40 which is less liable to crack at the junction between the first floor and the gable panels. My improved construction also provides a simple and effective connection between the gable end wall and the ceiling supporting and partition structures and avoids the necessity for special structural shapes, it being noted that herein only simple channels and plates are required.

While I have in this application described one embodiment which my invention may assume in 50 practice, it will be understood that this form of the same is shown for purposes of illustration, and that the same may be modified and embodied in various other forms without departing from the spirit or the scope of the appended claims.

55 What I claim as new and desire to secure by Letters Patent is:

1. In a building, a wall frame including members defining upper and lower panel apertures, wall panels in said apertures, and continuous 60 wall frame reinforcing means extending across the junction between said upper and lower panels.

2. In a building, a wall frame including members defining upper and lower panel apertures, wall panels in said apertures, and wall frame re- 65 enforcing means disposed in laterally spaced relation having integral portions extending across the junction between said upper and lower panels and fixed to the panel faces.

3. In a building, a wall frame including mem- 70 bers defining upper and lower panel apertures, wall panels in said apertures, and continuous wall frame reenforcing means extending outside the frame member comprising the junction between said upper and lower panels and fixed to the 75 panel faces.

4. In a building, wall frame members defining upper and lower panel apertures, wall panels in said apertures positioned by said frame members, and laterally spaced continuous rods on like faces of said panels having their ends positioned by spaced wall frame members and having integral intermediate portions extending across outside the frame member between said panels. 5

5. In a building, wall frame members defining upper and lower panel apertures, wall panels in 10 said apertures positioned by said frame members, coating anchoring material overlying the faces of said panels and said frame members, and rods disposed between said panels and said material, each of said rods having continuous portions ex- 15 tends over like faces of said panels and across the frame member between the panels and spacing said coating anchoring material from said panels and from the frame member between said 20 panels.

6. In a building, a wall frame presenting panel apertures and having spaced intermediate studs and gable corner studs, and a gable wall plate member connecting said studs and disposed above 25 the tops of the intermediate studs and below the tops of the corner studs. 35

7. In a building, a wall frame presenting panel apertures and having spaced intermediate studs and gable corner studs, a gable wall plate member connecting said corner studs and disposed 30 above the tops of the intermediate studs and below the tops of the corner studs, a joist disposed below the upper ends of said corner studs and along said plate member, and panel positioning means supported on the upper ends of said cor- 35 ner studs.

8. In a building, a frame including a corner stud comprising angularly related connected channels of different height, and a wall plate member supported on the upper end of a shorter 40 channel.

9. In a building, a frame including a corner stud comprising angularly related connected channels of different height, a wall plate member supported on the upper end of a shorter 45 channel, and a cooperating wall plate member connected to a longer channel of said stud below the upper end of said channel.

10. In a building, a wall frame including a corner stud comprising a plurality of angularly 50 related connected channels of different length, cooperating wall plate members supported on different channels below the upper end of a longer channel, and a connecting plate overlying the junction of one of said plate members with 55 its channel.

11. In a building, a gable wall frame including corner studs, cooperating plate means connecting said studs below the upper ends thereof, and roof supporting structure including connected 60 members supported on the upper ends of said corner studs, and means for positioning panels between said members and said plate means.

12. In a building, a corner stud including angularly related connected channels one of which is 65 shorter than the other, horizontal angularly related plate members secured to said corner stud adjacent the top of the shorter channel, a roof supporting member fixed to said stud adjacent the top of the longer channel, and a horizontal 70 joist secured to said corner stud and extending along one of said plate members and resting at one end on the other.

13. In a building, a wall frame including a sill member comprising an upwardly facing channel, 75

- upstanding stud members of story height having laterally directed channels, a plate member connecting the upper ends of said studs comprising downwardly and upwardly directed channels, 5
5. gable corner stud members projecting above said plate member and having laterally directed channels upstanding above said plate member, wall panels between said stud members having their edges positioned by the channels thereof and 10
- 10 received within the channels of said plate and sill members, and a roof supporting member connecting the upper ends of said gable stud members and comprising a downwardly directed channel receiving the upper ends of gable panels. 15
15. 14. In a building, a wall frame having connected frame members presenting panel apertures, and plate means connecting a multiplicity of said frame members at the junction of the same including inside and outside plates, said 20
- 20 inside plate having a laterally projecting ledge, and a laterally extending member fixed to said ledge perpendicularly to the inner plate. 25
15. In a building, upstanding stud members comprising laterally directed channel members, 25
- 25 and a plate member connecting the upper ends of said stud members having a downwardly directed channel, the flanges of which are located in the planes occupied by the channel flanges of said studs, the channel of said plate member having 30
- 30 its flanges cut away to receive the upper ends of said studs and said stud members and plate member being rigidly connected. 35
16. In a building, upstanding stud members comprising laterally directed channel members, 35
- 35 and a plate member connecting the upper ends of said stud members having a downwardly directed channel, the flanges of which are located in the planes occupied by the channel flanges of said studs, the channel of said plate member
- having its flanges cut away to receive the upper ends of said studs, and connecting plate means overlying the junction of said studs and plate member and fixed to both. 5
17. In a building, a wall frame including a sill 10
- 10 comprising an upwardly directed channel, a roof supporting member having a downwardly directed channel, an intermediate plate member having upwardly and downwardly directed channels, and stud members of channel section connecting 15
- 15 said roof supporting member and sill member with said plate, said stud members having the flanges of their channels located in the same planes as the channels of said plate, and also having their upper and lower ends received within 15
- 15 the channels of said roof supporting member and sill, said plate member having the flanges of its channels cut away at each junction with a stud to receive the end of the latter, and connecting plate means secured to said studs and plate member 20
- 20 on the opposite sides thereof at said junctions. 25
18. A prefabricated gable end wall section comprising a triangular frame presenting a plurality of panel apertures and having an oblique marginal frame portion at its top and a marginal frame portion at its bottom, and means carried on said bottom marginal portion and disposed at the ends of said portion and between said panel apertures for centering and connecting said section to a support. 30
19. A prefabricated gable wall section including a triangular frame comprising plate, stud and roof members of the wall, panel means positioned thereby, and connecting means for said 35
- 35 frame members also constituting means for centering and connecting said section to the remainder of the wall.

JOSEPH C. ESTES.
